ADJUSTABLE SOCKET

Filed March 24, 1928

Inventor:
Harry W. Vickery,
by Charles V. Tullar
His Attorney.

UNITED STATES PATENT OFFICE

HARRY W. VICKERY, OF LYNN, MASSACHUSETTS, ASSIGNOR TO GENERAL ELECTRIC COMPANY, A CORPORATION OF NEW YORK

ADJUSTABLE SOCKET

Application filed March 24, 1928. Serial No. 264,457.

My invention relates to socket devices and more particularly to devices of the type especially adapted for use in connection with electric lamps.

5 In connection with the use of electric incandescent lamps it is very often important that the lamp should be adjusted with respect to other apparatus which modifies the light produced by the lamp. It is an object of my 10 invention, therefore, to produce a socket device which may be readily adjusted, as for example, by the manipulation of the lamp itself.

15 The invention will be more fully understood from the following specification and claims, reference being had to the accompanying drawing, in which I show a number of different forms of sockets involving the features of the invention. It will be understood, 20 however, that I do not wish to be limited to the specific forms of socket shown, inasmuch as in view of the disclosure the devices may be modified without departing from the spirit of the invention or the scope of the 25 claims contained herein.

Referring to the accompanying drawing, Fig. 1 shows one form of casing for the device in perspective view from above. Fig. 2 is a perspective view of the casing from below. Fig. 3 shows the device in elevation holding a lamp. In one position of adjustment the lamp is shown in solid lines. In a different position the lamp is indicated by dotted lines. Fig. 4 shows in perspective 35 the socket element directly engaged by the lamp with the adjusting mechanism, all of which goes inside of the casing, Figs. 1 and 2. Fig. 5 is a so-called exploded view of the elements of the socket element, Fig. 4. Fig. 6 40 is a perspective view of a modified form of socket element, Fig. 4. Fig. 7 is an exploded view of the device, Fig. 6, corresponding to Fig. 5. Fig. 8 is a longitudinal section on line 8-8, Fig. 1, showing the relative positions of the elements of the socket and the casing. This section is taken along the teeth 45 15, Fig. 5.

Referring in detail to the drawing, the device comprises a casing 2, Fig. 1, of insulating material, on the top of which there may be

provided a plug consisting of the metal terminals 3 and 4. In Fig. 4 the lamp engaging socket element 5 is shown in operative engagement with the adjusting device 6. The central contact element 7 in this figure is connected by means of a flexible conductor 8 with a screw or bolt 9 which also serves to clamp the plug terminal 4 to the casing 2. Similarly, the outer, or shell, contact 5 which is in the form of a screw, is connected by means of a flexible conductor 10 with the bolt 11, which latter serves to clamp the terminal 3 to the casing 2. The bolt 11 also serves to clamp the rack 6 of the adjusting device to the casing 2. Referring to Fig. 2, it will be seen that the casing 2 is provided on the inside with a channel 12, within which the rack 6 is located. In section, the rack is channel-shaped, the teeth 13 being formed along one of the edges of the channel. The shell contact 5 is provided, as shown, with a set of one or more teeth 15 adapted to engage the teeth 13 in the rack. The spring element 16, one end 17 of the which is secured to the flange 14 and therefore to the shell 5 at a point just behind the teeth 15, constitutes a resilient means 65 which normally operates to force the teeth 15 into engagement with the teeth 13. It will be understood that the leg 18 of the spring engages the side 19 of the channel element 6 behind the flange 20. In adjusting the device the spring 16 is compressed by rotating the element 5, as indicated by the arrows, Figs. 4 and 5, with the result that the spring 16 is compressed and the teeth 15 are 70 disengaged from the teeth 13. When the teeth are thus disengaged, obviously the lamp and its socket may be slid in the casing 2 until the proper position for the lamp is reached. At this point the lamp is released and the tension of the spring 16 will force the teeth 15 75 back into engagement with the rack 6 thereby locking the lamp in position.

It will be seen that the devices, Figs. 6 and 7, are substantially the same as those shown in Figs. 4 and 5, the difference being that the flange 20 of the rack 6 is omitted, and a different form of spring device is substituted for the spring 16 of Fig. 5. This device comprises a bar 21 and a spring 22, the ends 23 80

and 24 of which engage the side 25 of the rack 26. In the device of Fig. 7 the teeth 15 of Fig. 5 are replaced by a rack element 28 secured to the side of the shell, the rear surface 29 of which is maintained in engagement with the side 30 of the bar 21. Obviously, by rotating the lamp in the direction indicated by the arrows, Figs. 6 and 7, the rack 28 is forced to compress spring 22, with the result that the teeth 28 disengage the rack teeth 31. Under this condition the lamp may be raised or lowered and when the rotary pressure is released, the spring 22 will again bring the teeth of the rack 28 into engagement with the teeth 31 of the rack element 26, thereby locking the lamp in its new position. With a device of this construction it is obvious that an incandescent lamp, such as lamp 32, may be easily and readily adjusted from one position in casing 2 to a new position by merely taking hold of the bulb, pressing up and down in the direction of the axis of the lamp until the desired position is reached, as for example, from the position indicated by the dotted lines of Fig. 3 to that represented by the solid lines. As is well understood, the contacts 3 and 4, when the socket is in use, are separated by means of a cutout film 33 between the upper ends thereof as indicated in Fig. 3.

What I claim as new and desire to secure by Letters Patent of the United States, is:—

1. In combination, a lamp socket, a casing for the socket, and latching means within said casing interposed between the casing and said socket whereby the socket may be unlatched, adjusted, and latched again with respect to the casing.
2. In combination, a lamp socket, a casing for the socket, and latching means within said casing interposed between the casing and said socket whereby the socket may be unlatched, adjusted, and latched again with respect to the casing, said latch comprising a pair of elements and a spring for maintaining said elements in latched engagement.
3. In combination, a lamp socket, a casing for the socket, and latching means within said casing interposed between the casing and said socket whereby the socket may be unlatched, adjusted, and latched again, with respect to the casing, said latch comprising a pair of elements and a spring for maintaining said elements in latched engagement, said spring and socket being under mutual control whereby by rotating the socket against the spring pressure the socket may be unlatched and whereby when the socket is left to the action of the spring it is again latched.
4. In combination, a lamp socket, a casing for the socket, and latching means within said casing interposed between the casing and said socket whereby the socket may be unlatched, adjusted, and latched again, with respect to the casing, said means comprising

an element secured to the casing and an element secured to the socket.

5. In combination, a lamp socket, a casing for the socket, and latching means within said casing interposed between the casing and said socket whereby the socket may be unlatched, adjusted, and latched again with respect to the casing, said latching means comprising an element secured to the casing and an element secured to the socket, and spring means for normally maintaining the two elements in engagement.

6. In combination, a lamp socket, a casing for the socket, and latching means within said casing interposed between the casing and said socket whereby the socket may be unlatched, adjusted, and latched again with respect to said casing, said latching means comprising a rack element secured to the casing and a tooth element secured to the socket, and spring means for normally maintaining the tooth in engagement with the rack, the spring being under the control of the socket whereby by rotating the socket the spring is pressed and the tooth disengaged from the rack.

7. In combination, a lamp socket, a casing for the socket, and latching means within said casing interposed between the casing and said socket whereby the socket may be unlatched, adjusted, and latched again with respect to the casing, said latching means comprising a rack element secured to the casing and a tooth element secured to the socket, and spring means for normally maintaining the tooth in engagement with the rack, the spring being under the control of the socket whereby by rotating the socket the spring is depressed and the tooth disengaged from the rack, and a channel in said rack enclosing said spring whereby the socket may be slid longitudinally of the rack, said socket being under the control of said spring whereby when the socket is released said spring operates to force said tooth back into engagement with said rack.

In witness whereof, I have hereunto set my hand this 22nd day of March, 1928.

HARRY W. VICKERY.
